UNITED STATES PATENT OFFICE

JOSEPH C. HOFFMAN, OF YONKERS, NEW YORK, ASSIGNOR TO J. C. HOFFMAN, INC., OF NEW YORK, N.Y., A CORPORATION OF NEW YORK

CONTAINER

Application filed August 7, 1931. Serial No. 555,703.

The invention relates to containers and more particularly to that type thereof in which the containers are made of pasteboard or similar material in cylindrical form for containing dry materials such as powders, crystals, cereals, etc. The object of the invention is to provide a novel closure for said containers whereby the latter are efficiently sealed and which when serving as a cover 5 is easily removed at will. The invention contemplates further the provision of an efficient cover or closure which itself is sanitary, and by reason of its form and construction is easily inserted into the container and which 10 is not unintentionally loosened by any changes in the physical dimensions of the container resulting for instance from the effects of atmospheric or other conditions. Other more specific objects will appear from 15 the description hereinafter and the features of novelty will be pointed out in the claims.

In the accompanying drawings, which illustrate several examples of the invention without defining its limits, Fig. 1 is a central 20 longitudinal section of a container with the novel closure combined therewith; Fig. 2 is a plan view showing the closure of Fig. 1 which serves as a removable cover; Fig. 3 is an elevation of a container, partly in section, 25 showing another form of the novel cover; Fig. 4 is an inverted plan view of the cover of Fig. 3; Fig. 5 is a fragmentary view of another arrangement of the closure; Figs. 6, 30 7 and 8 are detail sectional views showing additional forms of the novel closure; Fig. 9 is a plan view, with parts broken away, of the closure illustrated in Fig. 7; and Fig. 10 is a detail section of a further arrangement 35 of the novel closure adapted principally for 40 use as a bottom for the container.

In Figs. 1 and 2 the container is shown of cylindrical form with its body 15 or 15^a in the nature of a tube, it being understood that this is only an example for purposes of illustration and description, and not intended to define the limits of the field of usefulness of the novel closure.

Referring more particularly to Figs. 1 and 2, the body 15 is made of pasteboard or other 45 similar material in any customary manner

and is of cylindrical form with its opposite ends open, prior to the combination of the closure therewith. The lower end of the body 15, generally speaking, is permanently sealed by means of a closure which may embody the 55 novel features and constitute a bottom suitably secured in place in said body as by cementing or the like; the opposite or upper end of the body 15 is closed by means of the novel closure constructed in the form of a 60 cover capable of being easily removed from and inserted into said body 15 at will.

In the example illustrated in Fig. 1, the removable cover and the bottom are generally of similar construction, and each comprise an outer member comprising a disk, and preferably a flexible disk 16 or 16^a respectively, of suitable material, such as cardboard, sheet metal or the like, said disk 16 or 16^a customarily being made of cardboard or 65 its equivalent. The disk 16 or 16^a constitutes an independent element which is in permanent connection with an independent flange 17 or 17^a; any suitable means may be utilized 70 for connecting the disks with the flanges, the preferred arrangement being to provide the annular flange 17 or 17^a with a crimped bead 18 or 18^a to form an integral part of each flange and extending over the peripheral edge 75 of the disk, as illustrated. In the preferred 80 form the overlapping portion of the bead 18 is embedded in the disk 16 so as to lie substantially flush therewith as shown in the drawings; with this arrangement the external 85 surface of the closure is smooth and even and is free from any annular ridge against which dust or dirt might lodge. It will be obvious that the bead 18^a of Fig. 1 may be correspondingly combined with the disk 16^a, 90 as shown in Fig. 10. In addition, the closure includes a section comprising an integral extension of the flange, and co-operating means 95 extending from said section into engagement with the inner face of said outer member or disk 16 or 16^a for fixing the same against depression in the direction of the axis of the closure.

In the form shown in Fig. 1, the aforesaid integral section comprises a bottom 19 or 19^a, while the means whereby the disk or 100

outer member is fixed against depression consists of an arched section 20 or 20^a, comprising an integral part of the bottom 19. In both instances, the arched sections 20 and 20^a 5 extend into surface engagement with the inner face of the disk 16 and 16^a respectively, the arched section 20 being arranged and dimensioned to force the disk 16 to an outwardly flexed position, and to maintain it 10 therein; the arched section 20^a on the other hand is so proportioned that the disk 16^a is maintained in a flat position, as shown in Fig. 1.

As is clearly shown in Fig. 1, the closures 15 are of the plug type and are dimensioned so that the flanges 17 and 17^a snugly fit into the container 15 at opposite ends thereof with the crimped beads 18 and 18^a overlapping and engaging the opposite ends of said container. As previously stated, the bottom closure is preferably permanently secured in the container 15 in any convenient manner, as by cementing or gluing. The cover, on the other hand, is removably fitted into the 20 container 15 so as to be removable at will to render the interior of said container 15 accessible. In actual practice, it has been found that containers of the type in question, particularly when made of pasteboard or the 25 like, are subject to physical changes, such as shrinking resulting from atmospheric changes or other causes, so that the transverse dimensions of the container decrease. In the case of the customary type of cover 30 which slips exteriorly over the end of the container, such shrinkage tends to unintentionally loosen the cover whereby the sealing function thereof is rendered insecure and inefficient. With the present novel type of closure, the aforesaid shrinkage results in 35 clamping the cover more securely in place and results in an improved and more efficient sealing action therein. The novel construction of the closure permits the combination 40 of the outer member or disk, with the remainder of the closure in an efficient manner, which results in an attractive and thoroughly efficient seal; it also enables the disk or 45 outer member to be constructed of cardboard or other relatively inexpensive material and avoids the possibility that said disk will be unintentionally depressed in the direction of the axis of the closure to spoil the appearance thereof. The arrangement also enables 50 the disk or outer member 16 or 16^a to be printed or otherwise provided with advertising matter in a simple and easy manner prior to its connection with the flange of the closure.

55 In containers which comprise tubes 15^a of relatively heavy cardboard or other material which inherently develop a relatively large degree of friction on the flange 17 or its equivalent, it is generally preferable to provide the closure with suitable spacing devices

which, in the illustrated example shown in Figs. 3 and 4, are indicated as projections 21. These projections 21 are located at spaced intervals on the inner surface of the crimped bead 18 so as to extend downwardly therefrom into engagement with the end of the container 15^a when the closure is in position thereon. The crimped bead 18 is thus located at a slight distance from said end of the container to provide a space for the insertion of a prying implement, whereby said closure may be readily removed from the container at will. With such an arrangement, it may, in certain types of containers, be desirable to provide the same with a reinforcing band 22 70 of metal or other suitable material located at the end of said container which is engaged by the projections 21, as shown in Fig. 3. Instead of providing a bottom closure such as is illustrated in Fig. 1, the container may include a bottom closure 23 of any suitable type for instance, such as indicated in Fig. 3; this bottom closure is also permanently secured in the container in any suitable manner.

To provide a yielding or cushioning connection between the cover closure and the container such as 15, the latter may be provided interiorly at its one end with a cushioning bead 23 adapted to engage the flange 17 or equivalent and formed by rolling the material of which the container 15 is made, upon itself, as indicated in Fig. 5. With this arrangement a most efficient seal is provided between the cover closure and the container.

As shown in Fig. 6, the means whereby the disk or outer member is fixed against axial depression comprises an arched section 20^b which lies against the inner surface of the disk 16^b, and is so arranged as to force said disk 16^b into an outwardly flexed position and to maintain it therein. The arched section 20^b comprises an integral extension of a second flange 17^b located within the first flange 17 and connected therewith by a bend 17^c. The disk 16^b in the form now being described 105 may be connected permanently with the flange 17 by means of a crimped bead 18, as in the forms previously referred to.

In Figs. 7 and 8, the closure includes a bottom section 19^b comprising an integral part of the flange 17, and spacing devices engaging the opposed faces of said bottom section and disk to fix the latter against inward depression. The spacing devices, in the illustrated examples, comprise tubular members 20^c dimensioned in the direction of their axes to force the disk 16 to outwardly flexed positions and to maintain them therein, as shown in Figs. 7 and 8. In these forms of the closure, the disks 16 are permanently secured in place, for instance, by means of crimped beads 18, such as hereinbefore described. The form of the closure shown in Figs. 7 and 9 further includes a washer 24 arranged to fit over the tubular spacing mem- 125

ber 20^c and dimensioned to snugly fit within the flange 17, as clearly shown in Fig. 7. The washer 24 serves to prevent displacement of the tubular member 20^c and may be made of 5 cardboard or other suitable material; the tubular spacing member 20^c may likewise be constructed of cardboard or its equivalent.

In Fig. 10, which illustrates another form 10 of bottom closure, the arched section 20^d extends into engagement with the disk 16^c and is dimensioned so that said disk maintains an inwardly flexed position; the arched section 20^d engages the inner face of the disk 16^c and prevents inward depression thereof beyond the inward flexure indicated in Fig. 10; 15 otherwise this form of closure may be the same as the one illustrated in Fig. 1.

While the closures in all of the illustrated 20 examples are shown of circular form to fit containers of corresponding circular shape, it will be understood that the novel features 25 may be embodied in closures for non-circular containers. In all of its forms, the closure is of simple construction capable of being produced at relatively low cost to provide an 30 efficient closure for containers arranged to contain dry materials such as powders, crystals, cereals, etc. The closure is particularly adapted for use in connection with containers 35 for face powders and the like which in the most common form are referred to as compacts, in which case the arched sections provide spaces for the accommodation of powder puffs when the closure is in place on the container.

Various changes in the specific forms 40 shown and described may be made within the scope of the claims without departing from the spirit of the invention.

I claim:

1. A closure of the kind described comprising a non-metallic disk, an independent metallic flange in permanent connection with the periphery of said disk and overlapping the outer surface thereof in substantially flush relation to said surface, and an arched metallic section comprising an integral part of said flange and extending into surface engagement with the inner face of said non-metallic disk.

2. A closure of the kind described comprising a flexible non-metallic disk, an independent flange in crimped connection with said disk and overlapping the outer surface thereof in substantially flush relation to said surface, and an arched metallic section comprising an integral extension of said flange dimensioned to engage said non-metallic disk and fix it in an axially flexed position.

3. A closure of the kind described comprising a flexible non-metallic disk, an independent flange in crimped connection with said disk and overlapping the outer surface thereof in substantially flush relation to said surface, and an arched metallic section

comprising an integral extension of said flange dimensioned to engage said disk and force it to an outwardly flexed position and maintain it therein.

4. A closure of the kind described comprising a flexible disk, an independent annular flange, an annular crimped bead forming an integral part of said flange for permanently connecting the disk therewith, spacing devices projecting from said bead in the direction of the axis of said flange and constituting a support for the closure in use and means whereby said disk is fixed against axial depression. 70

5. A closure of the kind described comprising a flexible non-metallic disk, an independent annular flange, an annular crimped metallic bead forming an integral part of said flange and overlapping the outer surface of said disk in substantially flush relation to said surface for permanently connecting the disk with said flange, projections located at spaced intervals on the inner surface of said bead and constituting spacing devices, and an arched metallic section comprising an integral part of said flange and extending into surface engagement with the inner face of said non-metallic disk. 80

6. A closure of the kind described comprising a flexible non-metallic disk, an independent flange in crimped connection with said disk and overlapping the outer surface thereof in substantially flush relation to said surface, and a metallic bottom comprising an integral continuation of said flange, and including an arched section extending into engagement with the inner face of said non-metallic disk to fix the same against axial depression. 90

7. A closure of the kind described comprising a flexible non-metallic disk, an independent flange in crimped connection with said disk and overlapping the outer surface thereof in substantially flush relation to said surface, and a metallic bottom comprising an integral continuation of said flange, and including an arched section extending into engagement with the inner face of said non-metallic disk, said arched section being dimensioned to force said disk to an outwardly 100 flexed position and to maintain it therein.

8. The combination of a hollow container, and a closure therefor, said closure comprising a flange adapted to interiorly fit an end of said container, a crimped bead forming an integral part of said flange and arranged to project outwardly therefrom over said end of the container, an independent flexible disk permanently connected with said crimped bead, means whereby said disk is fixed against axial depression, and projections located at spaced intervals on said crimped bead for engagement with said end of the container to space said bead there- 110 120 125 130

from whereby the removal of said closure from said container is facilitated.

9. A closure of the kind described comprising a flexible disk, an independent annular flange, an annular crimped bead forming part of said flange and having an overlapping portion embedded in and lying substantially flush with said disk for permanently connecting the latter with said flange, and means whereby said disk is fixed against axial depression.

10. A closure of the kind described comprising a non-metallic section consisting of a flexible disk, and a metallic section crimped over the peripheral edge of said disk in countersunk relation to the outersurface thereof, said metallic section including an annular flange and an arched portion contacting with the inner surface of said non-metallic disk to maintain the same against axial deflection.

In testimony whereof I have hereunto set my hand.

JOSEPH C. HOFFMAN.
